ABSTRACT

A sifter or separator particularly for use in connection with grain milling machines provides for continuous circulation of air along a closed pathway within the apparatus. The material to be sifted is introduced in said circulatory stream of air at one point thereof, while the coarse portion of the material is removed from said stream by impingement against a rotary screen which permits finer particles of the material to pass into a cyclone where they are removed from the air stream by centrifugal action and gravity. Inlet and outlet valves are of the type which when operated permits passage of the material while at the same time substantially preventing passage of air regardless of operative position.

SIFTERS FOR GRAIN AND CHEMICAL INDUSTRIES

This invention relates to a sifter or separator for a variety of different materials although of particular advantage in connection with grain milling machines for the purpose of separating the coarser particles of grain from the fine ingredients.

An object of the invention is to provide a sifter or separator of the kind indicated which requires very little space without loss of efficiency.

A further object of the invention is to provide a sifter of the type indicated in which the material to be sifted is entrained by a stream of air which circulates along a closed pathway wholly within the apparatus, thus eliminating the need for air filters.

Another object of the invention is to provide a sifter of the kind indicated which is inexpensive to manufacture and to operate, particularly due to the absence of air filters and consequent need for cleaning and replacement of the same.

Other objects and advantages of the invention will become apparent from the following detailed description thereof.

A preferred embodiment of the invention is described below with reference to the accompanying drawing in which

FIG. 1 is a diagrammatic perspective view of the sifter or separator,

FIG. 2 is a diagrammatic top plan view of the same, and

FIG. 3 shows, on a larger scale, a vertical section through the sifter or separator on line III-III in FIG. 2.

In the drawing, a housing 10 comprises two parallel vertical end walls 12, 14 which are interconnected along their edges by a side wall 16 the upper portion of which is cylindrical and extended downwardly substantially in the form of a V. Along the edges of said V-shaped extension of the side wall the end walls 12, 14 are inclined downwardly towards each other to thus form with the side wall 16 a funnel-shaped portion 18 at the bottom of the housing 10. Said funnel-shaped portion 18 opens into a bottom pipe 20 in which a control valve 22 is mounted. The housing 10 is supported on four legs 24 and a base plate 26, or in any other suitable manner.

A horizontal shaft 30 is mounted in suitable bearings 32 in the end wall 12 of housing 10 and extends therethrough perpendicularly to the end walls 12, 14 at the center of the upper cylindrical portion of the housing 10. Said shaft 30 carries on its outer end portion a pulley 34 and on its other end within the housing 10 a circular screen 35 which thus is rotatable on the axis of the shaft 30 when a source of driving power is applied to the pulley 34 as, for example, by means of a motor, indicated at 36, a drive pulley 38 and a V-belt 40.

A U-shaped pipe or tube 44 is supported by a bracket 46 secured to the upper portion of the housing 10 and extending upwardly therefrom. A horizontal leg 48 of said pipe extends into the housing 10 through the end wall 12 thereof into close vicinity of the screen 35. The other leg 50 of the U-shaped pipe is secured to and communicates with the interior of a ventilator 52 which comprises a housing 54 in which an impeller 56 is mounted for rotation on a vertical shaft 58 of a drive motor 60 secured to the top wall of the ventilator hous-

ing 54. A supply pipe 62 communicates with the leg 50 of the U-shaped pipe 44 and is provided with a control valve 64.

Below the ventilator 52 a cyclone 66 is disposed which comprises an upper cylindrical portion 68 with a top closure 70 and a downwardly tapering lower portion 72 with a bottom outlet pipe 74 provided with a control valve 76. The cyclone 66 is supported on a horizontal pipe section 78 which is secured to the cylindrical upper portion 68 of the cyclone 66 and to the end wall 14 of the housing 10 to establish communication between the interiors of said cyclone 66 and housing 10.

Within the housing 10 the pipe section 78 terminates in a conical member 80, the wide end of which is disposed in close vicinity to the screen 35 and in axial alignment with the leg 48 of the U-shaped pipe 44. The pipe section 78 is curved in the horizontal plane as indicated by dotted lines in FIG. 2 so as to provide an inlet to the cyclone 66 which is directed tangentially of said cyclone. A pipe section 80 extends downwardly from the bottom wall of the ventilator 52 centrally thereof into the cyclone 66 within the cylindrical portion 68 thereof, and the portion of said pipe section 80 disposed within the cyclone 66 is provided with a number of perforations 82, as shown.

The valves 64, 22 and 76 are of the type, well known in the art, which when rotated either continuously or intermittently permit passage of granular material while at the same time in any rotary position substantially preventing passage of air. Said valves may be operated manually or automatically in any desired sequence by suitable means (not shown).

In operation when the impeller 56 is rotated by its drive motor 60 a stream of air is forced out through the U-shaped pipe 44 towards the rotating screen 35 and through pipe 78 of cyclone 66, perforations 82 and back through pipe 80 into the ventilator 52. In passing the open inner end of supply pipe 62 said stream of air carries with it the material from said supply pipe 62, and when said entrained material forcefully hits the screen 35, coarser particles in the material are prevented from passing through said screen and fall downwardly in the housing 12 towards the valve 22. Finer particles of the material pass through the rotating screen 35 and enter through the funnel-like portion 80 into the pipe 78 from where they pass tangentially into the cyclone 68 and are flung due to centrifugal action along the interior wall of the cylindrical portion 68 of said cyclone 66 whereupon they gradually drop downwardly through the tapered portion 72 of the cyclone toward the valve 76. The air thus substantially free from entrained material is returned to the ventilator 52 and recirculated along the path indicated above.

It is obvious, therefore, that due to the continuous circulation of the air within the apparatus and the continuous removal of entrained material in the housing 10 and the cyclone 66 there is no need for any filters at any place in the apparatus. This is one of the outstanding advantages of the present invention, naturally resulting in substantially reduced manufacturing and operating costs and in greatly reduced space requirements, all without any detrimental effect on the efficiency of the apparatus.

The invention is not limited to the embodiment shown and described but numerous modifications are

feasible within the limitations of the appended claims.

What I claim is:

1. A sifter for separating coarse and fine particles from each other, particularly in connection with grain milling machines, comprising
  - a. a housing mounted on a support base and having a bottom outlet,
  - b. a sifter screen of substantially flat configuration,
  - c. means supporting said screen within said housing for rotation on a substantially horizontal axis,
  - d. means for rotating said screen on said axis,
  - e. a ventilator housing disposed adjacent to said screen housing,
  - f. a ventilator mounted in said ventilator housing for rotation on a vertical axis,
  - g. ventilator drive means connected with said ventilator,
  - h. a cyclone beneath said ventilator housing and having a circular cross-section in a horizontal plane and a bottom outlet,
  - i. a tubular member secured to said ventilator housing and extending downwardly therefrom into said cyclone centrally of said ventilator and said cyclone and provided with a plurality of apertures distributed around the circumference of the portion of said tubular member extending into said cyclone,
  - j. a substantially U-shaped tubular member connecting the interior of said ventilator housing with the interior of said screen housing, one leg of said U-shaped tubular member ending close to said screen at a distance from the center of said screen,
  - k. a pipe section having one end in close vicinity to the opposite side of said screen from said one leg of the U-shaped tubular member and being aligned therewith, the other end portion of said pipe section being secured to said cyclone and opening into the same in a tangential direction thereof,
  - l. a supply pipe connecting said U-shaped tubular member with a source of supply for the material to be sifted, and
  - m. a valve in each of said supply pipe and said bottom outlets of the screen housing and the cyclone, said valves being of the type substantially preventing air passage in all operative positions while being oper-

ative to permit passage of granular material, whereby a stream of air propelled by said ventilator from said ventilator housing passes in a closed pathway through said U-shaped tubular member into said screen housing, through said rotating screen, into and through said pipe section, tangentially into said cyclone to be whirled around along the cylindrical interior wall thereof, through said plurality of apertures and back through said tubular member into the ventilator housing thereby entraining the material to be sifted from said supply pipe and causing coarse particles in said material to impinge against said rotating screen and fall downwards in the screen housing toward the bottom outlet thereof, while finer particles pass through the screen and into the cyclone to be subjected to centrifugal action and fall downwardly toward the bottom outlet of said cyclone.

2. A sifter for separating coarse and fine particles from each other, particularly in connection with grain milling machines, comprising a ventilator, a housing enclosing a rotary disc type screen, and a cyclone; tubular means interconnecting said ventilator, screen housing and cyclone so as to form a closed pathway through said elements; supply means for controlled introduction of the material to be sifted into said pathway; and valve means in said supply means, said screen housing and said cyclone, said valve means being of the type substantially preventing passage of air therethrough in all operative positions while permitting controlled passage of sifted material, and said tubular means comprising a first U-shaped tubular element connecting said ventilator with said screen housing and ending in close vicinity to one side of said rotary screen, a second tubular element aligned with the outlet portion of said first U-shaped tubular element and extending from the vicinity of the other side of said screen into said cyclone tangentially of said cyclone, and a third tubular element providing communication between said cyclone and said ventilator and having a portion extending into said cyclone to a level below said second tubular element and being provided in the downwardly extending portion with a plurality of small apertures.
